152,998

DESIGN FOR A STAND OR SIMILAR ARTICLE

Manuel Martin, Los Angeles, Calif.

Application March 17, 1947, Serial No. 137,690

Term of patent 7 years

(Cl. D33—14)

To all whom it may concern:

Be it known that I, Manuel Martin, a citizen of the United States, residing at Los Angeles, in the county of Los Angeles and State of California, have invented a new, original, and ornamental Design for a Stand or Similar Article, of which the following is a specification, reference being had to the accompanying drawing, forming a part thereof, in which:

Fig. 1 is a perspective view of a stand or similar article, showing my new design;

Fig. 2 is a front elevational view;

Fig. 3 is a side elevational view; and

Fig. 4 is a bottom end view.

I claim:

The ornamental design for a stand or similar article, as shown.

MANUEL MARTIN.
